UNITED STATES PATENT OFFICE

149,672

DESIGN FOR A FLASHLIGHT

Eugene H. Phillips, Glendale, Calif., assignor to
Lennan Lights, Inc., Burbank, Calif.

Application July 1, 1946, Serial No. 131,219

Term of patent 14 years

(Cl. D48—24)

To all whom it may concern:

Be it known that I, Eugene H. Phillips, a citizen of the United States of America, residing in the city of Glendale, in the county of Los Angeles, State of California, have invented a new, original, and ornamental Design for a Flashlight, of which the following is a specification, reference being had to the accompanying drawings, forming a part thereof.

Figure 1 is a perspective view of a flashlight showing my new design;

Figure 2 is an elevational view thereof;

Figure 3 is a top plan view of the flashlight; and Figure 4 is a bottom plan view of the same.

I claim:

The ornamental design for a flashlight, substantially as shown.

EUGENE H. PHILLIPS.
